UNITED STATES PATENT OFFICE.

JOHN C. WEILER AND GOTTLIEB KLEISSLER, OF NEWARK, NEW JERSEY.

GRAVITY SASH-LOCK.

949,165.

Specification of Letters Patent. Patented Feb. 15, 1910.

Application filed April 16, 1909. Serial No. 490,355.

To all whom it may concern:

Be it known that we, JOHN C. WEILER and GOTTLIEB KLEISSLER, citizens of the United States, residing at Newark, in the county 5 of Essex and State of New Jersey, have invented certain new and useful Improvements in Gravity Sash-Locks; and we do hereby declare the following to be a full, clear, and exact description of the invention, such as 10 will enable others skilled in the art to which it appertains to make and use the same, reference being had to the accompanying drawings, and to characters of reference marked thereon, which form a part of this 15 specification.

The invention has reference, generally, to improvements in windows, skylights, and the like, such as doors and shutters; and, the invention relates, more particularly, to 20 a novel construction of gravity-lock for use, preferably, with metal windows, skylights, doors, shutters, and the like the lock being especially adapted for use with a flexible connection, such as a chain, and an inter- 25 mediately disposed fusible connection or link, for retaining the window, skylight, door, or the like, in an open position, but the lock acting automatically to close the open window, skylight, door, or the like, 30 when the flexible connection is unhooked, or when the fusible connection or link is melted in case of excessive heat, due to fire.

The present invention has for its principal object to provide in connection with a window, skylight, door, shutter, and the like, a simple and cheaply constructed, as well as a positively operating gravity lock which works by gravity to retain the window, or the like, in its closed position, but can be 40 readily manipulated to open the window, or the like, all with a view of entirely dispensing with the use of any springs which are apt to become weak and useless, due to corrosion or when exposed to fire.

45 Other objects of this invention are simplicity in construction, and a reduction of the parts to a minimum, thereby providing a locking-mechanism in which the parts can not get out of order and are always in readiness to be operated, or to effectively lock the window, or the like, when closed.

With the various objects of the present invention in view, the invention consists, primarily, in the novel gravity-lock here- 55 inafter set forth; and, the invention consists, furthermore, in the novel arrange-

ments and combinations of the various devices and parts, as well as in the details of the construction of the same, all of which will be more fully described in the following specification, and then finally embodied in the clauses of the claim which are appended to and which form an essential part of the said specification.

The invention is clearly illustrated in the accompanying drawings, in which:

Figure 1 is a face view of a metallic window-frame and a hinged or pivoted metallic window-sash arranged so as to swing in said window-frame, provided with a gravity-lock embodying the principles of the present invention, and showing in connection therewith a flexible connection and a fusible link, the parts being represented in their normal initial position, when the window-sash is 60 locked by means of the gravity-lock. Fig. 2 is a similar view of the same parts, showing the window-sash unlocked and swung out into its opened position in the window-frame. Fig. 3 is a transverse vertical section of the portions of a metallic window-frame and window-sash, showing in side elevation the lock-construction, with the locking-dog thereof in its locked or holding engagement with a part of the window-sash 65 to retain the same in its closed position, said view being made on an enlarged scale. Fig. 4 is a similar view of the parts represented in said Fig. 3, with the parts of the lock in their disengaged positions, just prior to the 70 swinging-out movement of the window-sash, said view being made on a larger scale, than that of Fig. 2. Fig. 5 is a view similar to that represented in said Fig. 4 of the drawings, but showing the positions of the respective parts of the lock, prior to the swinging-in or closing movement of the window-sash. Fig. 6 is a perspective view of the 75 dog-releasing element or lever of the lock; and Fig. 7 is a similar view of a frame or 80 casing in which said dog-releasing element or lever is operatively arranged. Fig. 8 is a top or plan view of the sash-releasing dog and the frame or casing in which it is 85 mounted; and Fig. 9 is a bottom view of the 90 said parts. Fig. 10 is a transverse vertical section of the upper portions of a metallic window-frame and window-sash, and a side elevation of a slightly modified form of sash-releasing dog, the dog-releasing element or 95 lever being, however, omitted from this 100 view.

Similar characters of reference are employed in all of the above described views, to indicate corresponding parts.

Referring now to the several figures of the drawings, the reference-character 1 indicates a metallic window-frame, of any usual construction, the same being provided with a hollow portion 2, forming a chamber, substantially as shown in the several figures of the drawings. In the lower wall or base 3 of the portion 2 is a suitable hole or opening 4, and suitably secured upon this wall or base 3, by means of screws 5, or in any other suitable manner, is a suitably formed frame 6. The latter is provided with suitably formed members or arms, as 7, and is provided with screw-threaded holes 8 for the reception of the screw-threaded shanks of said screws 5. The said members or arms 7 form with the front-portion 9 of said frame or casing an opening, as 10, the wall 11 of which may be made to taper downwardly, substantially as shown in Figs. 3, 4, 5 and 10 of the drawings. Extending across the opening 10 is a pin or rod 12, said pin or rod having its end-portions suitably connected with said members or arms 7, and oscillating freely upon said pin or rod 12, and within the space or opening 10, is a window-sash releasing element or dog 13. This dog is eccentrically pivoted upon said pin or rod 12, so that when the window-sash has been brought into its opened position, as will be hereinafter more fully described, the said dog 13 will hang vertically as indicated in Fig. 5 of the drawings. As shown, the said dog is made upon one of its portions, with an arc-shaped edge 14, as shown in the several figures of the drawings, and which may be left perfectly plain as indicated in Fig. 10, or may be provided upon a portion thereof with laterally extending projections or serrations, as 15, and as clearly illustrated in Figs. 3, 4 and 5, of the drawings. The previously mentioned window-frame is also made with a downwardly extending part, as 16, against which the upper portion of the window-sash is brought, as represented in said Fig. 3 of the drawings, when the window-sash is in its closed position.

In the present form of metallic window, the said sash which is pivoted in any suitable manner in the window-frame, is indicated by the reference-character 17, the window-sash being made in its upper part with a hollow portion or chamber 18, which is ordinarily closed by the metal end-piece 19, shown more particularly in Fig. 2 of the drawings, said end-piece being suitably soldered or otherwise secured upon the metal strips 21 forming a part of the metal framework of the window-sash. In its front face-portion the window-sash 17 is made with a suitably formed opening 22, while the said

end-piece 19 is also provided with an opening, as 23. Suitably secured within the said hollow-portion or chamber 18, by means of screws 24, or other suitable fastening means, is a suitably formed frame or casing, as 25. This frame, as will be seen more particularly from an inspection of Fig. 7, comprises an open rectangular frame-like element 26 which is provided with the screw-threaded holes 27. Extending downwardly from each longitudinal member of the said frame-like element 26 are suitable ribs or projections 28, said ribs or projections being formed with screw-threaded holes 29, and the rib or projection at the front of said frame-like element 26 being provided with an opening 30 which is bounded by a forwardly and downwardly tapering surface, as 31. As shown, the said ribs or projections 28 are preferably of slightly greater thickness than that of the frame-like element 26, so as to provide suitable off-sets, as 32, at the front and rear of the respective ribs or projections 28, so as to properly fit the said frame or casing 25 in the upper portion of the chamber 18 of the window-sash, substantially in the manner clearly illustrated in Figs. 3, 4, 5 and 10 of the drawings, being secured in said position by means of the said screws 24 having their screw-threaded shanks screwed into the screw-threaded holes 27. When the said frame or casing 25 has been secured in its fixed position, the opening 30 in the front rib or projection 28 is directly back of the opening 22 in the front face-portion of the window-sash, as clearly shown in the said figures of the drawings.

Movably arranged within the open part of the said frame or casing 25, so as to be adapted to engage with the window-sash releasing dog herein-before described, is a suitably formed dog-releasing element or lever, as 33. This dog-releasing element or lever comprises a heavy head or member 34 preferably of the general configuration herein shown, although the shape of the said head may be departed from, and extending from the said head or member 4 and projecting into and through the previously mentioned openings 30 and 22 is an arm or finger 35 to the free end-portion of which is suitably attached, preferably in a hole or eye 36 for the purpose, a flexible connection 37, as a chain or the like, by means of which the lock-mechanism can be operated and the window-sash swung open and held in its opened position when a link of the said chain is hooked over a hook-shaped holding device, as 38, and as shown in Fig. 2. In any suitable portion of the said chain there may be placed a fusible connection or link, as 39, which melts due to excessive heat in case of fire and allows the window-sash to close of its own accord, as will be clearly understood. Having thus described the general ar- 130

angement and construction of the various parts of the gravity-lock, we will briefly set forth its operation.

Suppose the window-sash to be moving 5 in the direction of the arrow x , in Fig. 5, from its opened position to the closed position shown in Fig. 3, the window-sash releasing dog hanging vertically, as shown in said Fig. 5. The quick movement of the 10 upper rear edge-portion of the window-sash against the said vertically hanging dog, immediately causes the dog to be swung or oscillated upwardly, practically in the position shown in Fig. 4. At the same time, the 15 window-sash assumes its vertical and closed position in the window-frame, and the said dog in attempting to assume its former vertical position, drops partially into the upper open part of the window-sash, substantially in the manner illustrated in Figs. 20 3 and 10 of the drawings, causing a portion of the lower curved edge of the said dog, or one of the projections or serrations in the said curved edge-portion to effectively engage and bind with a portion of the open-frame or casing 25 in the manner illustrated, so that on account of the eccentrically pivoted dog, and the weight thereof, the window-sash is positively retained in its closed position, against accidental opening of the same. 30 In the meantime, the oscillatory dog-releasing arm or lever assumes its normal initial position, at rest, and as clearly indicated in said Fig. 3.

When it is desired to open the window-sash, a pull upon the flexible connection or chain moves the upper portion of the head of the dog-releasing device against the curved edge-portion of the window-sash 35 releasing dog, thus causing the parts of the lock-mechanism to assume the positions indicated in Fig. 4 of the drawings, and by continuing to pull upon the flexible connection or chain, the window-sash can be 40 moved or swung open in the direction of the arrow y in said Fig. 4, and retained in its open position in the manner shown in Fig. 2 of the drawings.

From the foregoing description of the 50 present invention, it will be clearly seen, that we have produced a simply constructed and efficiently operating gravity lock for the purposes stated, in which the use of all springs is avoided so that the parts of the lock can not possibly get out of order.

We are aware that some changes may be made in the general arrangements and combinations of the devices and parts, as well 55 as in the details of the construction of the said parts, without departing from the scope of the present invention as set forth in the foregoing specification. Hence, we do not limit our invention to the exact arrangements and combinations of the devices and 60 parts as described in the said specification,

nor do we confine ourselves to the exact details of the construction of the said parts, as illustrated in the accompanying drawings.

We claim:

1. The combination, with a hollow metallic frame and a hollow fixture, as a window, door, or the like, pivotally connected with said frame, said fixture having an opening in its upper portion normally registering with an opening in said metallic frame, of a locking mechanism connected with said frame and said fixture comprising a releasing-dog pivotally connected with said frame and having a portion normally extending partly through the registering openings in said frame and said fixture and in holding engagement with said fixture, and means connected with said releasing dog for the disengagement of said releasing dog from said fixture. 70

2. The combination, with a hollow metallic frame and a hollow fixture, as a window, door, or the like, pivotally connected with said frame, said fixture having an opening in its upper portion normally registering with an opening in said metallic frame, of a locking mechanism connected with said frame and said fixture comprising a releasing-dog pivotally connected with said frame and having a portion normally 90 extending partly through the registering openings in said frame and said fixture and in holding engagement with said fixture, and an oscillating element connected with said fixture, said element comprising a head 95 adapted to be forced into engagement with said releasing dog for the disengagement of said releasing dog from said fixture, and an arm extending from said head for actuating said dog-releasing element. 100

3. The combination, with a hollow metallic frame and a hollow fixture, as a window, door, or the like, pivotally connected with said frame, said fixture having an opening in its upper portion normally registering with an opening in said metallic frame, of a locking-mechanism connected with said frame and said fixture comprising an eccentrically pivoted releasing-dog 110 formed with an arc-shaped grasping surface normally extending partly through the registering openings in said frame and said fixture and in holding engagement with said fixture, and means connected with said fixture adapted to be forced into holding 115 engagement with said releasing dog for the disengagement of said releasing dog from said fixture. 120

4. The combination, with a hollow metallic frame and a hollow fixture, as a window, door, or the like, pivotally connected with said frame, said fixture having an opening in its upper portion normally registering with an opening in said metallic frame, of a locking-mechanism connected 125

with said frame and said fixture comprising an eccentrically pivoted releasing-dog formed with an arc-shaped grasping surface normally extending partly through the registering openings in said frame and said fixture and in holding engagement with said fixture, and an oscillating element connected with said fixture, said element comprising a head adapted to be forced into engagement of said releasing dog from said fixture, and an arm extending from said head for actuating said dog-releasing element.

5. The combination with a metallic window-frame and a metallic window-sash pivotally connected with said frame, said window-frame as well as said window sash being provided with chambered portions, a frame in the chambered portion of said window-frame, said frame comprising a pair of arms formed with an open space between them, a releasing-dog eccentrically pivoted between said arms, said dog having an arc-shaped grasping surface, a frame in the chambered portion of said window-sash, said last-mentioned frame being provided with downwardly extending ribs, one of said ribs being formed with an opening, and the said window-sash being provided with an opening registering with the opening in said rib, and an oscillating element in said

last-mentioned frame, said element comprising a head arranged between said ribs, said head being adapted to be forced in engagement with said releasing dog, and an arm connected with said head and extending through the openings in said rib and the window-sash for actuating said releasing element.

6. A gravity lock comprising a frame 40 formed with a pair of arms having an open space between them, a releasing dog pivoted in said space, said dog having an arc-shaped grasping surface, a second frame provided with downwardly extending ribs, one of 45 said ribs being formed with an opening, and an oscillating element in said last-mentioned frame, said element comprising a head arranged between said ribs, said head being adapted to be forced in engagement with said releasing dog, and an arm connected with said head and extending through the opening in said rib for actuating said releasing element.

In testimony that we claim the invention 55 set forth above we have hereunto set our hands this 14th day of April, 1909.

JOHN C. WEILER.
GOTTLIEB KLEISSLER.
